(57) **CLAIM**

The ornamental design for a television receiver, as shown and described.

DESCRIPTION

FIG. 1 is a perspective view of a television receiver showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a rear perspective view thereof showing the state in which the camera lens has been inserted into the inside;

FIG. 10 is a reference view showing the state that the connecting part of the camera can be detached;

FIG. 11 is a perspective view showing the state that the connecting part of the camera has been completely detached;

FIG. 12 is a front view of FIG. 11;

FIG. 13 is a rear view of FIG. 11;

FIG. 14 is a left side view of FIG. 11;

FIG. 15 is a right side view of FIG. 11;

FIG. 16 is a top plan view of FIG. 11;

FIG. 17 is a bottom plan view of FIG. 11;

FIG. 18 is a rear perspective view of FIG. 11; and,

FIG. 19 is a reference view showing the state that the connecting part of the camera has been detached and then the television receiver has been connected to the corresponding bracket on the wall.

The broken lines shown illustrate portions of the television receiver that forms no part of the claimed design.

1 Claim, 19 Drawing Sheets
